UNITED STATES PATENT OFFICE

EDWARD J. GLACKIN, OF CHICAGO, ILLINOIS.

SPRING-WHEEL.

1,071,153.

Specification of Letters Patent. Patented Aug. 26, 1913.

Application filed October 6, 1909. Serial No. 521,308.

To all whom it may concern:

Be it known that I, EDWARD J. GLACKIN, a citizen of the United States, and a resident of Chicago, in the county of Cook and State 5 of Illinois, have invented certain new and useful Improvements in Spring-Wheels, of which the following is a full, clear, and exact specification.

My invention is concerned with the elastic 10 wheels of the class in which springs or other elastic cushions are interposed between the hub and the rim, so that jars on the rim are absorbed by the springs or cushions, and if they reach the hub at all, their effect is 15 minimized so as to produce an easy riding vehicle, and it is designed to produce a wheel of the class described, in which the degree of elasticity can be readily regulated to adapt it for different roads and for different loads.

Another object of my invention is to construct a wheel of the class described in which the spring connections between the hub member and the rim member shall have 25 only frictional engagement, thereby increasing the efficiency of the wheel.

Another object of my invention is to produce a device of the class described in which any one of the springs may be taken out 30 and replaced without disturbing the remaining springs.

Another object of my invention is to produce a wheel of the class described in which the tension of the springs shall be distributed more uniformly than has been possible 35 with wheels of this type heretofore devised.

Finally, it is an object of my invention to produce a wheel of the class described which shall have the advantages noted and which 40 shall be strong and durable, simple and inexpensive to manufacture, and which shall be efficient in its operation.

To illustrate my invention, I annex hereto two sheets of drawings in which the same 45 reference characters are used to designate identical parts in all the figures, of which—

Figure 1 is a side elevation of the wheel with a portion of the upper part of the covering removed and broken away; Fig. 2 is 50 a section on the line A—A of Fig. 1; Fig. 3 is an enlarged detail in perspective illustrating the construction of the individually removable segments connecting the outer and inner annuli of the rim member; Fig. 4 is 55 an enlarged detail substantially in section on the line B—B of Fig. 1; Fig. 5 is a per-

spective view of a filling block; Fig. 6 is a detail in section illustrating the coöperation of the cover plates and the segments; Fig. 7 is a perspective view of one of the 60 removable cover plates; Fig. 8 is an enlarged detail of a portion of Fig. 2; and Fig. 9 is a perspective view of a filling block which I may employ.

In its general construction, it will be seen 65 that my wheel is made up of a rim member which carries the tread, and within which is located a hub member adapted to rotate on an axle in the ordinary manner, and between the two members are interposed the 70 springs by which the two members are permitted to move relatively to each other so that the shock may be absorbed thereby.

In the preferred form of my invention, the hub member consists of the ordinary 75 hub 10 having the spokes 11 and the felly 12, upon which is secured the hub annulus 13 which consists of a strong circular band of steel resembling a tire but very much wider and extending to either side a considerable distance beyond the felly. The basis of the rim member is three annuli, the outer one 14 of which is of the same width as the hub annulus 13, while the two inner ones 15 are much narrower and are separated a sufficient distance to permit the passage of the spokes 11 between them. The 80 rim annulus 14 has supported above it at its outer edges by the riveted studs 15 the two narrow annuli 16, and the tread material 17, which may be composed of leather, rubber, or any other desired material, is supported outside of the annuli 14 and 16. The 85 basis of the annuli 15 from the annulus 14 I provide the segments 18, which are 90 preferably removable, and which preferably have the following construction. Each one is provided with the outer and inner flanges 95 19 and 20, respectively, and the flange 19 has formed therein the bayonet slot 21 which is adapted to coöperate with the stud 15 to secure the segment in its inner position 100 in a manner that will be readily understood. Between the flanges 19 of the segments are strips 22, which, together with the studs 15, 105 serve to space the annulus 14 and the annuli 16 apart a proper distance, and after the segment 18 has been put in place, a filling block or strip 23 is pushed in between the flanges 19 and the adjacent ends of the strips 22 in the manner indicated in dotted lines in Fig. 3. The annulus 14 has the

recess 24 formed therein to receive the turned down flange 25 of the filling block. The flange 20 is adapted to pass beneath the annulus 15, and a screw 26 is passed through an aperture in the flange and screwed into a threaded aperture in the annulus 15. By the connections thus described it will be readily apparent that the segments 18 can be readily removed while it is desired to give out and remove any of the springs to be described.

To keep out the dust, and close the spaces between the segments 18, I provide the removable cover plates 27, one of which is shown in perspective in Fig. 7, which are preferably thinner than the segments 18 and have their edges adapted to slip in beneath the undercut edges 28 of the segments 18 in the manner shown in Fig. 6. When the cover plates 27 are in place they can be secured by screws 29 passed through apertures in the ears 30 on the cover plates and screwed into the threaded recesses in the downwardly projecting lugs 31 forming the outer edges of the annuli 15. I preferably provide an aperture 32 in the upper edge of the cover 27, through which a screw may be passed and threaded into a suitable aperture formed in the edge of the spacers 22, or the annuli 14, as may be desired. To cover the spokes, I preferably provide the disks 33, which have the central apertures 34 therein of sufficient size to permit of the necessary relative movement between the hub and the rim members without interference with the hub proper, and these disks may be secured in place by screws 34 passed through apertures in the edges thereof and into threaded apertures in the ears 35 turned down on the inner edges of the annuli 15, as best shown in Fig. 2.

Upon the outer surface of the annulus 13 I secure the U-shaped casings, the open ends of which are adapted to be closed by the end pieces 37 which are removably secured thereto, preferably by the screws 38. Within this U-shaped casing 36 I mount the blocks 39, which have the centers of the bolt springs 40 secured thereto and an adjusting screw 41 is threaded through the spring and block and has its inner end bearing against the outer surface of the annulus 13, and by this means it will be readily seen that I can adjust the tension of the spring as may be desired by turning the screw 41 in or out. Where the spring is put under considerable tension so as to raise the bottom of the block 39 any appreciable distance above the outer surface of the annulus 13, I preferably slide in between the bottom of the block and the top of the annulus a filling block 42 of the proper width, shown in Fig. 9, and provided with the open slot 43 to permit the passage of the screw 41. When this filling block 42 has been put in place, the screw is

preferably manipulated so as to bring the block 39 promptly upon the filling block 42, thus relieving all the pressure on the screw which would tend to strip the threads. The ends of the springs 40 are rounded off, as shown, and they have only frictional engagement with the inner surface of the annulus 14, so that the hub member is free to adjust itself in any necessary angular relation to the rim member.

In carrying out my invention, I preferably employ two other sets of springs 44, which are similar to the springs 40, but are similarly supported upon the outer surface of the annuli 15, so that they can be removed or replaced, and are likewise provided with similar adjusting screws to regulate the tension.

While I have shown and described my invention as embodied in the form which I at present consider best adapted to carry out its purposes, it will be understood that it is capable of modifications, and that I do not desire to be limited in the interpretation of the following claims except as may be necessitated by the state of the prior art.

What I claim as new, and desire to secure by Letters Patent of the United States is:

1. In a wheel, the combination with a rim member, of a hub member, the inner periphery of the rim member extending within the outer periphery of the hub member, one set of bowed springs interposed between the outer periphery of the hub member and the inner periphery of the rim member, and another similar set interposed between the outer periphery of the rim member and the outer periphery of the hub member, the two members being attached only frictionally, the ends of the springs being free to slide on the member to which they are not attached.

2. In a spring wheel, the combination with a rim annulus, of a hub annulus, bowed springs having their ends engaging one annulus, blocks held in position on the other annulus and having the center of the springs secured thereto, and screws threaded through the blocks and having their ends engaging the annulus upon which the blocks are supported.

3. In a spring wheel, the combination with a rim annulus, of a hub annulus, bowed springs having their ends engaging the one annulus, a casing on the other annulus having one end removable, blocks held in position by said casings and having the centers of the springs secured thereto, screws threaded through the blocks and having their ends engaging the annulus upon which the blocks are supported, and filling blocks adapted to be interposed between the under sides of the spring supporting blocks and the annulus.

4. In a spring wheel, the combination

with the two concentric rigidly connected rim annuli, of the hub annulus between the rim annuli, and springs secured to two of the said annuli and having frictional engagement only with the other annuli so that the angular relations of the hub annulus with the rim annuli may be shifted to any extent.

5. In a spring wheel, the combination with the single outer broad rim annulus and two narrow inner rim annuli, of a single broad hub annulus between the outer and inner rim annuli having its spokes extending between the two inner rim annuli, 10 springs attached to the inner rim annuli and having their free ends frictionally engaging the hub annulus, similar springs attached to the hub annulus and engaging the outer rim annulus, and individually removable segments connecting the outer and 15 inner rim annuli.

6. In a spring wheel, the combination with two concentric rim annuli, of a hub annulus between the rim annuli, springs interposed between said annuli, and individually removable segments connecting the outer and inner rim annuli. 25

7. In a spring wheel, the combination with two concentric rim annuli, of a hub annulus between the rim annuli, springs interposed between said annuli, individually removable segments connecting the outer and inner rim annuli, and individually removable segmental cover plates interposed between the removable segments. 30

In witness whereof, I have hereunto set my hand and affixed my seal, this 30th day of September, A. D. 1909.

EDWARD J. GLACKIN. [L. S.]
